The ornamental design for a remote positioning pneumatic plug, as shown and described.

DESCRIPTION

FIG. 1 is a side elevational of a view of a remote positioning pneumatic plug, showing our new design the opposite side being a mirror image thereof, except for the omission of the cotter pin and eye bolt;

FIG. 2 is a front elevational view thereof;

FIG. 3 is a top plan view thereof; and,

FIG. 4 is a rear elevational view thereof.

The handle shown broken away in FIGS. 1-4 is to indicate the indeterminate length of the elongated handle member.
